FLUID EXPANDED PISTON FOR OIL PUMPS

Filed June 11, 1927

UNITED STATES PATENT OFFICE

JOHN F. MITCHELL, OF COTTON VALLEY, LOUISIANA, ASSIGNOR OF FORTY-FIVE PER CENT TO LEWIS G. WILLIAMS, OF COTTON VALLEY, LOUISIANA

FLUID-EXPANDED PISTON FOR OIL PUMPS

Application filed June 11, 1927. Serial No. 198,160.

The object of this invention is to provide an oil pump in which the piston or plunger is of elongated tubular form and includes a valve retaining device or cage, that portion 5 of the tubular element or sleeve above the cage being expansible under fluid pressure due to the weight of the column of oil or other fluid in the well casing.

A further object is to provide a piston or 10 plunger of the type indicated, and in connection therewith a removable valve seat which may be threaded into the lower end of the plunger, and which includes a tubular scraping device designed to remove from the 15 wall of an inner element of the well casing any sand or other foreign material,—an annular space being afforded between the scraping element and the lower end of the piston, to permit sand or the like, tending 20 to collect here, to pass thru ports toward the center of the combined valve seat and scraping element, and to pass into the main stream of fluid flowing from the well.

With the foregoing and other objects in 25 view, the invention consists in the novel construction and arrangement of elements described, illustrated and claimed, it being understood that modifications may be made within the scope of the claim without de- 30 parting from the spirit of the invention.

In the drawings forming part of this application,

Figure 1 is a view in vertical section, thru the well casing and thru the tubular piston 35 or plunger.

Figure 2 is a similar view, the piston being on the downward stroke, whereas in Figure 1 it was on the upward stroke.

Figure 3 is a transverse section on line 3—3 40 of Figure 1, looking in the direction of the arrows.

Figure 4 is a transverse section on line 4—4 45 of Figure 1, in the direction of the arrows.

Figure 5 is a transverse section on line 5—5 50 of Figure 1, also in the direction of the arrows.

A section 10 of the well casing is connected by a sleeve or coupling 11 with that section of the casing designed to receive the piston or plunger, said element 11 having an upper in-

ner threaded portion 12, and a lower externally threaded portion 13. Portion 13 cooperates with the internally threaded end of casing section 14, the latter receiving a sleeve 15 in which the piston or plunger operates. This arrangement permits of the renewal of element 15, when required, and this element abuts at its upper end the end of portion 13, when the parts are screwed up 55 tightly. A slight space at 16 permits of the necessary longitudinal movement of the elements in order to secure proper connection.

The lower end portion of sleeve 15 abuts the externally threaded end of the sleeve or coupling 18, and the internally threaded end 60 of casing section 14 engages a corresponding portion on said sleeve 18, space being provided if desired at 19, for the purpose previously indicated.

A lower sleeve or coupling 20 may be provided with a flange 21, and this element 20 is threaded into sleeve 18, and permits of the connection of another pipe section below 65 said element 20, if desired. A removable valve seat 23 is threaded into the upper end 70 of said element 20, and a ball valve 24 cooperates with this seat, and operates within a cage structure 25.

The piston rod 27 has threaded connection 75 at 28 with the piston which includes a spider-like structure 29 having the threaded head 29', the elongated tubular element constituting the piston per se being shown at 30, and being expansible under the weight of the column of oil or other fluid in the well casing, so that no packing is required, the outer wall of element 30 coming into contact with the bore of element 15 constituting the inner 80 portion of that section of the casing in which the piston or plunger operates.

A ball valve 32 cooperates with threaded 85 and removable seat 33, the latter cooperating with the internally threaded portion 34 of the tubular piston.

This element 33, the upper end of which 90 constitutes the seat, has formed integrally therewith a lower extension 35 constituting a tubular scraping or cleaning device, for the purpose of removing from the bore of the casing section 15 any foreign material which 95 100

may tend to collect thereon. The material so removed passes into the main stream of oil flowing from the casing and pumped by the mechanism just described.

5 An annular space 36 between the scraping element 35 and the end portion 34, permits of the passage therethru of sand or the like, which may tend to flow downwardly in the casing, the material passing thru ports 37, 10 and entering the main stream of oil, so that wear, or undue wear on the casing section 15 is avoided, by the removal of all foreign material, so far as it is possible to effect this result. A slightly reduced diameter may be 15 provided at 34, to avoid any tendency to bind, due to the generation of heat, the upper portion of the expansible piston being sufficiently flexible to produce a practically fluid-tight contact, without undue friction.

20 What is claimed is:—

20 In a device of the class described, a well casing, a piston operating within said casing and having an upper open and unobstructed end portion provided with thin expansible 25 walls of uniform thickness, the piston including a tubular extension having a lower open end acting as a casing cleaning element, the extension having a reduced portion providing an annular chamber at the end of the 30 tubular piston, the extension being provided with ports extending radially thereof, to provide for the passage of material from the annular chamber to the inner portion of the extension.

35 In testimony hereof I affix my signature.
JOHN F. MITCHELL.
